ELECTRODE HOLDER

Cecil R. Fitch, St. Paul, Minn.

Application November 22, 1939, Serial No. 305,736

4 Claims. (Cl. 219—8)

This invention relates to a holder for electrodes particularly as used in connection with electric arc welding.

It is aimed to provide an improved and simplified construction in effect having but a single movable part, and especially one which is insulated to the maximum extent to increase safety by making the holder contact proof especially so that it will not be dangerous if the holder is laid down or accidentally touches a metal part in contact with the weld.

The more specific objects and advantages will become apparent from a consideration of the description following taken in connection with accompanying drawing illustrating an operative embodiment.

In said drawing:

Figure 1 is a view of the device in central longitudinal section;

Figure 2 is a fragmentary central longitudinal section but showing an electrode in place;

Figure 3 is a horizontal section taken on the line 3—3 of Figure 1, and

Figure 4 is an elevation of the inner end of the holder.

Referring specifically to the drawing wherein like reference characters designate like or similar parts, I provide a tube or pipe 10, preferably metallic and for instance of brass, which may be crooked as shown, so that the holder may generally be of pistol grip form.

The tube 10 has a straight portion 11 and within the tube at the inner end of the latter, an abutment block 12 of brass is secured as by means of a rivet 13. An expansive coil spring 14 of suitable metal abuts one end of the block 12 and said spring in turn is abutted by the inner end of a plunger 15 of brass or other suitable material. Said plunger 15 forwardly of the tube 10 has an enlarged head 16 secured to the plunger as by means of a screw 17 and which head is adapted for manual engagement for pushing inwardly against the tension of the spring 14 from the position of Figure 1 to the position of Figure 2. Said head 16 is made of a suitable fire-resistant insulating material.

Surrounding the forward portion 11 of the tube 10, is a sleeve 18 of fiber or other insulation, which may be secured thereto by means of a bolt or the like as at 19. Extending through the portion 11 and sleeve 18, are diametric openings or holes 20 and 20', respectively, the former being preferably slightly larger than the latter. The aforesaid bolt 19 extends through a slot or kerf 21, provided through the plunger 15, and

one end wall thereof as at 22, is cut at the same angle as the openings 20.

As a result of the construction described, when the head 16 is pushed inwardly, the kerf 21 will align with the openings 20 so that an electrode 23 as commonly used in arc welding, may be placed through the openings 20 and kerf 21 and held in place therein through the expansive action of spring 14 which moves the wall 22 into contact with the electrode. The action of the spring is sufficient to hold the electrode in place against danger of accidental disengagement and in conducting relation with the metallic tube 10.

It will be noted that the bolt 19 also extends through the slot or kerf 21, thus holding the plunger in position for effecting the alignment of the slot 21 with the openings 20.

Rearwardly of the portion 11, tube 10 has a curved or grip portion 24 and the latter is surrounded by a sleeve 25 of soft or pliable rubber or other suitable insulation and a relatively large ring 26 of fiber or other suitable insulating material, surrounds the tube 10 between the sleeves 18 and 25, forming an effective guard against slippage of one's hands forwardly into contact with the electrode. Ring 26 may be fastened to the tube by a set screw 27.

At the inner end, a head 28 is employed, having an opening 29, through which a conducting electric cable C is passed and fastened within the conducting tube 10, by soldering, by wedging, or in any other approved manner. The head 28 consists of a nut or ferrule 30, for instance of copper, which may be screwed as at 31 to the exterior of the pipe or tube 10. Fibre or any other suitable insulation as at 32, surrounds the periphery of the ferrule 30, being effectively fastened thereto as by means of a screw 33, and the corners of the insulation 32 preferably being flattened as at 34. Fiber or other insulating washers are used at 25a and 25b so that ferrule 30 and the metallic wires of conductor C will not be exposed.

Various changes may be resorted to provided they fall within the spirit and scope of the invention.

I claim as my invention:

1. An electrode holder having a tube of conducting material, a plunger operable in said tube, said plunger and tube having openings adapted to align to receive and hold an electrode, spring means urging disalignment of the openings of the plunger and tube, means extending from the tube through the opening of the plunger to guide the plunger and prevent rotation thereof rela-

tively to the tube and insulation about the tube held in place by said means.

2. An electrode holder having a tube of conducting material, a plunger operable in said tube, said plunger and tube having openings adapted to aline to receive and hold an electrode, spring means urging disalignement of the openings of the plunger and tube, means extending from the tube through the opening of the plunger to guide the plunger and prevent rotation thereof relatively to the tube, insulation about the tube held in place by said means, and a manually operable head on the forward end of the plunger beyond the forward end of the tube recessed at the inner end to extend over the adjacent end of the tube.

3. An electrode holder having a tube of conducting material, a plunger operable in said tube, said plunger and tube having openings adapted to aline to receive and hold an electrode, spring means urging disalignement of the openings of the plunger and tube, means extending from the tube through the opening of the plunger to guide the plunger and prevent rotation thereof relatively to the tube, a manually operable head on the forward end of the plunger beyond the forward end of the tube, said tube having a crooked portion, insulation about said crooked portion, a sleeve about the forward end of the

tube, said means also passing through said sleeve to hold it in place and a guard ring between said sleeve and said insulation.

4. An electrode holder having a tube of conducting material, a plunger operable in said tube, said plunger and tube having openings adapted to aline to receive and hold an electrode, spring means urging disalignement of the openings of the plunger and tube, means extending from the tube through the opening of the plunger to guide the plunger and prevent rotation thereof relatively to the tube, a manually operable head on the forward end of the plunger beyond the forward end of the tube, said tube having a crooked portion, insulation about said crooked portion, a sleeve about the forward end of the tube, said means also passing through said sleeve to hold it in place, and a guard ring between said sleeve and said insulation, a manually operable head on the forward end of the plunger beyond the forward end of the tube recessed at the inner end to extend over the adjacent end of the tube, a ferrule secured to the inner end of the tube through which a cable is adapted to pass to the tube, and insulation disposed peripherally of the ferrule.
